UNITED STATES PATENT OFFICE.

NICK SCHLEICH, OF GREAT FALLS, MONTANA.

HOBBYHORSE.

Application filed November 24, 1925. Serial No. 71,127.

This invention relates to a wheeled device in which a figure is mounted to be propelled by the rider and at the same time have a vertical reciprocating movement imparted thereto.

The invention consists of a hobby horse, a wheeled base therefor, cushioned guide means between the figure and the base, drive mechanism adapted to be operated by the rider to both propel and impart an up and down movement to the figure, and novel steering means for directing the device as it is propelled.

While the drawings illustrate a preferred embodiment of the invention it is to be understood that in adapting the means to meet specific needs and requirements the design may be varied, and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a side view of a hobby-horse, embodying the invention.

Figure 2 is a view of the device inverted, or as seen from the bottom side.

Figure 3 is a vertical, longitudinal sectional view on the line 3—3 of Figure 2 looking in the direction of the arrows.

Figure 4 is a vertical transverse sectional view on the line 4—4 of Figure 3 looking towards the rear as designated by the arrows.

Figure 5 is an enlarged detail sectional view on the line 5—5 of Figure 3.

Figure 6 is a sectional view, similar to Figure 3, showing a modification in which the drive gearing includes a tumbling drive shaft, and

Figure 7 is an enlarged detail sectional view on the line 7—7 of Figure 6.

Corresponding and like parts are referred to in the following description and designated in the several views of the drawings by like reference characters.

The device comprises essentially a wheeled base, a figure mounted upon the base in a manner to receive an up and down movement, a drive gearing for controlling the device and at the same time imparting a vertical reciprocating movement to the fig-

ure, and steering mechanism for directing the device as it is propelled.

The base comprises longitudinal bars 1 and transversely spaced upright side pieces 2. An axle 3 mounted upon the rear ends 60 of the longitudinal bars 1 receives wheels 4 which are fast thereto and revolve therewith, for propelling the device. The front ends of the longitudinal bars 1 curve upwardly and forwardly, as indicated at 5, to 65 clear the front wheel 6 which is utilized for steering purposes and which is journaled in a fork 7 at the lower end of a post 8 which extends vertically and is mounted in a tube 9 rising from the front end of the base. 70 Guide tubes 10 and 11 project vertically from opposite end portions of the base, the rear guide tube 11 being mounted upon an arch 12 formed by a cross piece and uprights. 75

The figure approximates the outline of a horse and is mounted upon the base to have a vertical reciprocating movement imparted thereto and is maintained in place and directed in its vertical movements by suitable 80 guide means, including posts 13 and side pieces 14, the latter operating between the side pieces 2 and the posts 13 operating in the guide tubes 10 and 11. The figure comprises a back 15 and side pieces 16, the latter being spaced at their lower edges to loosely engage the outer faces of the side pieces 2. The posts 13 depend from opposite ends of the back 15 and have a telescopic fit within the guide tubes 10 and 11. 85 Cushioning means are interposed between the figure and base and, in the preferable construction, consist of coil springs 17 located within the guide tubes 10 and 11 and engaging the lower ends of the posts 13. 90

The drive mechanism comprises a crank shaft 18 having pedals 19 which are oppositely disposed and this crank shaft is mounted in the side pieces 14 so as to move vertically with the figure. Vertical slots 20 100 are formed in the upper portions of the side pieces 2 and provide clearance for opposite end portions of the crank-shaft 18. An eccentric 21 fast to the crank-shaft 18 receives a strap 22 of a rod 23 which is pivotally 105 connected at its lower end to the base, as indicated at 24, the connection consisting of a rod supported at its ends in the longitudinal bars 1. It will thus be understood that as the crank-shaft 18 is rotated it, at the 110

same time, is moved up and down through the instrumentality of the eccentric 21, strap 22, and connecting rod 23. Since the crank-shaft 18 is mounted upon the figure it is clear that the latter has a vertical reciprocating movement imparted thereto.

The rear axle 3 may be connected to the crank-shaft 18 in any determinate way to have a rotary movement imparted thereto whereby to propel the device simultaneously with the up and down movement of the figure. In the construction shown in Figures 2, 3 and 4, a sprocket wheel 25 fast to the crank-shaft 18, is connected by means of a sprocket chain 26 to a sprocket wheel 27 fast to the rear axle 3. In the construction shown in Figures 6 and 7 a bevel gear wheel 28 is fast to the crank shaft 18 and a tumbling shaft 29 forms connecting means between the crank shaft 18 and the rear axle 3.

The tumbling shaft 29 comprises a plurality of sections which are connected by universal joints and a bevel pinion 20, at one end of the shaft, is in mesh with a bevel gear wheel 32 fast to the rear axle 3. It is observed that power may be transmitted from the crank-shaft 18 to the rear axle 3 in any preferred way according to the caprice of the manufacturer and the design of the device.

The steering of the device may be effected in any determinate way and, as indicated in Figure 6, the upper portion of the post 8 is adapted to operate through an opening 33 in the head of the figure, and a handle bar 34 is fitted thereto, so that the rider mounted upon the figure may grip the handle bar and effect a steering of the device as the same is propelled.

In the form shown most clearly in Figures 3 and 5 of the drawings, a handle bar 35 is fitted to the upper end of the steering post 8 and is located wholly within the head of the figure and crossed lines 36, attached to the ends of the bar 35, pass through openings 37 in the sides of the head and extend within convenient reach of the rider to be manipulated to properly steer the device as the same is propelled. From the foregoing it will be readily understood that a child or other individual operating the device sits astraddle the back of the figure, and operates the crank-shaft 18 through the pedals 19 in a manner well understood in the operation of a bicycle or other vehicle propelled by foot power. Rotation of the crank-shaft 18 effects a propelling of the device and a vertical reciprocating movement of the figure and the one mounted thereon and, as the device advances, it is steered through the wheel 6 and the post 8 in the manner set forth.

Having thus described the invention, I claim:

1. A manually propelled device, comprising a wheeled base, a figure mounted upon the base in a manner to move vertically, a crank-shaft mounted upon the figure, and an eccentric connection between the crank-shaft and base for imparting an up and down movement to the figure when the crank-shaft is rotated. 70

2. A manually propelled device, comprising a wheeled base, a figure mounted upon the base in a manner to move vertically, a crank-shaft mounted upon the figure, an eccentric connection between the crank-shaft and base for imparting an up and down movement to the figure when the crank-shaft is rotated, and connecting means between the crank-shaft and a supporting wheel of the device to simultaneously propel the same with the up and down movement of the figure. 80 85

3. A device of the character specified comprising a base, a figure mounted upon the base in a manner to receive a vertical reciprocating movement, guide means between the figure and base, a crank-shaft mounted upon the figure, and an eccentric connection between the crank-shaft and base for imparting an up and down movement in the figure when the crank-shaft is rotated. 90

4. A device of the character specified comprising a base, a figure mounted upon the base to move vertically, guide and cushioning means between the figure and base, a shaft mounted upon the figure and adapted to have a driving force applied thereto and an eccentric connection between the said shaft and base whereby to impart an up and down movement to the figure when the shaft is rotated. 95 100

5. A device of the character specified, a wheeled base, a figure mounted upon the base for vertical movement, telescoping guide members between the figure and base, cushioning means associated with the guide members, a shaft mounted upon the figure, and an eccentric connection between said shaft and base. 105 110

6. In a device of the character specified, a wheeled base, spaced side pieces rising vertically from the base, a figure mounted upon the base and comprising side pieces embracing the side pieces of the base, a shaft mounted upon the figure and an eccentric connection between said shaft and base. 115

7. In a device of the character specified, a wheeled base, a figure mounted upon the base for vertical movement, a steering post disposed within the figure, and lines having a portion exterior to the figure and a portion within the figure and crossed and connected to the steering post to effect a reverse movement thereof according to which one of the exterior lines is drawn upon. 120 125

8. A device comprising a wheeled base, a figure of a horse mounted upon the base to 130

receive a vertical movement, guide and cushioning means between the figure and base, a steering post disposed within the figure, means associated with the steering post to admit of the same being controlled from a point exterior to the figure, a crank-shaft carried by the figure, an eccentric con- nexion between the crank-shaft and base, and connecting means between the crank-shaft and a supporting wheel of the base 10 to propel the device simultaneously with the up and down movement of the figure.

In testimony whereof I affix my signature.

NICK SCHLEICH. [L. s.]
